UNITED STATES PATENT OFFICE.

EMILE JOSEPH AUGUSTIN SCHULTZ, OF PARIS, FRANCE.

ECONOMICAL LUBRICANT-DISTRIBUTER FOR MECHANICAL INSTALLATION.

1,379,219.

Specification of Letters Patent.

Patented May 24, 1921.

Application filed October 22, 1918. Serial No. 259,243.

To all whom it may concern:

Be it known that I, EMILE JOSEPH AUGUSTIN SCHULTZ, a citizen of the Republic of France, and resident of Paris, France, 5 have invented a certain new and useful Improvement in Economical Lubricant-Distributers for Mechanical Installations, of which the following is a specification.

The present invention has for its object a 10 lubricant distributer adapted to supply to different members of a mechanical installation, whose parts move in dependence one of another, exactly essential quantities of oil, at each operation, without recourse to throttling of distributing ducts leading to the members, which are always exposed to choking or obstructions and have consequently an uncertain function.

This result is obtained by allowing the 20 lubricant to flow freely and by effecting the division of the liquid streams by means of knives surmounting channels inclined in opposite directions, thereby causing the separation of each stream into two parts, this system of division being applied at the outlet of the oil pump and on the streams obtained successively until there are a sufficient number of stream parts. The apparatus, moreover, permits of an automatic regulation of 30 the discharge.

The invention will be clearly understood with the aid of the drawing accompanying the present description, which drawing is given by way of example and in which—

35 Figure 1 is an elevation of the apparatus, and

Fig. 2 is a plan view.

Oil arrives from the pump by the tube J on the pivoting pan L, balanced by a counter-weight P and adapted to oscillate between two stops t t'. It remains horizontal while the oil is flowing from tube J at rest against stop t'. In this horizontal position, the lubricant spreads itself over the pan and flows in thin streams through the openings l l arranged at the sides. In this way, it is seen that the flow of liquid is interrupted immediately the motor stops, because the pump being motionless no more oil comes.

50 The openings l have a V shape form; they cannot become choked or obstructed. An end rectangular outlet y, whose outlet end is slightly raised, with respect to the outlet ends of the other outlets, allows excess liquid

to pass into the receptacle R which communicates with the pump feed reservoir.

A second regulating plate T, situated below the first, can be set obliquely by means of the controlling screw V so as to collect, as circumstances may require, or according 60 to the viscosity of the liquid or any other purpose, one or more streams flowing from the upper platform L. The other streams fall into the receptacle R, which, as previously stated, communicates with the pump. 65

It is of the quantity of liquid collected on platform T that a division is made for distribution to the different members. The first division into two parts is made on the liquid which flows freely by duct x on to a 70 projecting edge s situated in the middle of a trough S. The flow through the succeeding troughs S', S'', S''' arranged horizontally and at a little distance one from the other, results in the division of the said two first 75 parts into respectively 4, 8 and 16 parts.

A similar arrangement is symmetrically disposed on the other side of the distributer and allows a corresponding number of subdivided parts to be produced. A lubricant 80 of another kind can be distributed by such a second series of troughs.

It will be seen that the flow of the lubricant brought to this state of retarded dropping by a single flow in free air, cannot be 85 interrupted as it would be by very small openings, slits or cracks, provided to limit and restrict the flow.

There will not be any interruption between the distributer and the lubricator 90 feed inlets if care be taken to use connecting ducts relatively large for the quantities to be distributed. Such ducts can be constituted by metallic tubes of several millimeters bore.

95 The quantity of oil can be varied for the different degrees of frictions in one and the same machine. The quantity of liquid can be effected by any suitable division and trough where this quantity is sufficiently 100 known.

105 It is evident that the arrangements described above are in no way limited and can, while remaining within the scope of the invention, be modified, both as regards regulation details and the disposition and mounting of various parts, as may be necessary for particular cases.

Having thus described the nature of the said invention and the best means I know of carrying the same into practical effect, I claim:—

- 5 1. In an oil distributing apparatus, the combination with an oil delivery member, of means comprising a tilttable pan for receiving oil from said member and having oil delivery openings, for arresting the flow 10 of oil from the openings contemporaneously with the cessation of oil flow from said member.
- 15 2. In an oil distributing apparatus, according to claim 1 characterized by an oil receiving receptacle to receive oil from the oil delivery openings and having an outlet and means comprising a knife edge for effecting a division of the oil stream flowing from said outlet.
- 20 3. In an oil distributing apparatus, according to claim 1 characterized by an adjustable collecting pan adapted to be placed in such position as to receive the oil flowing from any number of said delivery openings.
- 25 4. In an oil distributing apparatus, according to claim 1 characterized by an oil receiving receptacle to receive oil from the oil delivery members and having an outlet, means comprising a knife edge for effecting a division of the oil stream flowing from 30 said outlet into two parts, receptacles having outlets for collecting each of said streams and means comprising a knife edge for effecting a division of the oil streams

flowing from the outlets of the last-named 35 receptacles.

5. In an oil distributing apparatus, the combination of a pivoted counter-weighted pan for receiving oil and having openings, a movable collecting pan for receiving the 40 oil flowing from the openings of the pivoted pan and having an outlet duct and an edged member to separate the oil flowing from the duct.

6. In an apparatus for distributing oil, the 45 combination of a pivoted counter-weighted pan, adapted to receive oil from an oil delivery member having on one side of its pivotal point a plurality of openings from which the oil passes toward the elements to be lubricated and on the other side of the pivotal point an opening, the outlet end of which is raised above the outlet ends of the other openings, the excess oil in the pan 50 flowing through said opening.

7. In an oil distributing apparatus, the combination with a delivery member, of means comprising an oil tilttable pan to receive oil from the oil delivery openings having delivery openings for arresting the 60 flow of oil from its openings contemporaneously with the cessation of oil flow from said member into a pan and means to limit the movement of the tilttable pan.

In witness whereof I have hereunto signed 65 my name.

EMILE JOSEPH AUGUSTIN SCHULTZ.
